UNITED STATES PATENT OFFICE.

WILLIAM J. KEENE, OF CHICAGO, ILLINOIS, ASSIGNOR TO CHICAGO SPRING HINGE COMPANY, OF CHICAGO, ILLINOIS, A CORPORATION OF ILLINOIS.

SPRING HINGE.

Application filed August 9, 1923. Serial No. 656,595.

To all whom it may concern:

Be it known that I, WILLIAM J. KEENE, a citizen of the United States, and a resident of Chicago, county of Cook, and State 5 of Illinois, have invented certain new and useful Improvements in Spring Hinges, of which the following is a specification.

My invention relates to double-acting spring hinges which are normally held in 10 a neutral position and are adapted to swing to either side of the neutral position against a spring tension which acts to return the hinge to the normal or neutral position.

The principal objects of my invention are 15 to provide an improved construction affording convenient adjustment of the neutral position; to effect the adjustment by operation of a single member; to construct the adjusting mechanism so that it may be 20 readily incorporated in a small, compact bracket; and to provide a spring hinge housing which may be attached to a door or gate with a minimum amount of cutting and fitting.

25 On the drawings:

Fig. 1 is a fragmentary view of a gate or door attached to a support by means of a spring hinge embodying my invention;

Fig. 2, a sectional view on the line 2—2 30 of Fig. 1, with parts broken away to disclose details of the construction; and

Fig. 3, a top view of the housing of the spring hinge mechanism taken on the line 3—3 of Fig. 1.

35 Referring to the drawings, the numeral 1 indicates a gate or door which is mounted to swing on the support 2, said gate being provided at the upper end adjacent the inner edge with a recess 3 having a plate secured therein and provided with an upwardly projecting pin 4 engaging in an aperture 5 of the bracket 6 which latter is secured by the bolts 7 to the support 2. A similar bracket 8 is secured to the support 40 2 at a distance below the bracket 6 by means of the bolts 9 and has an arm 10 provided with an aperture 11 in axial alignment with the aperture 5 of the bracket 6. A bushing 12 is engaged in the aperture 11 and provided with an annular flange 13 around the upper end which is seated in a corresponding recess 14 in the arm 10, so that the upper surface of the bushing 12 is flush with the upper surface of the arm 10 and this bushing 45 55 is provided with an arm 15 extending

laterally in a wide recess 16 in the top of the arm 10.

The walls of the arm 10 at opposite sides of the recess 16 have aligning apertures 17 loosely engaged by a screw 18 which is 60 threaded through the outer extremity of the arm 15 and held against axial displacement by the head 19 at one end and the nut or washer 20 at the other end, the latter being held in place on the end of the screw by upsetting or riveting over the end of the screw against the outer face of the nut or washer, as indicated at 21. The apertures 17 are preferably enlarged at their outer ends to accommodate the head 19 and 65 a nut or washer 20, as shown in Fig. 2, so that these parts do not project beyond the sides of the arm 10.

Operation of the screw 18 serves to swing 70 the arm 15 laterally in the recess 16 around an axis concentric with the aperture 11 and the apertures 17 are sufficiently large to provide for such displacement of the screw 18 as occurs by reason of the swinging of the arm 15 with which the screw is engaged. 75

The bushing 12 has a square aperture 22 preferably tapered from the upper to the lower end to receive the correspondingly formed lower end 23 of the spindle 24 of a spring hinge of any suitable type, such, 80 85 for example, as a spring hinge of my application, Serial No. 506,738, filed October 10, 1921.

In spring hinges of this character it is sometimes necessary to have an adjustment 90 for correcting a tendency of the hinge to assume an improper neutral position, or it is frequently desirable to arrange the hinge so that the gate or door will stand somewhat ajar or to one side or the other of a 95 central position, as shown by dotted lines at 25 in Fig. 2, and the adjusting screw 18 serves to afford the desired adjustment for either purpose and permits such adjustment to be readily effected as it requires only the 100 adjustment of the single member 18.

In applying spring hinges of this character to gates or doors, it is desirable to avoid the necessity of accurate cutting or fitting of the door or gate in order to 105 install the hinge properly thereon, and to this end I have constructed the hinge casting 26 which is of circular cross section, as shown in Fig. 3, with a flat face 27 at one side, of substantially the thickness of 110

the door or gate so that a square-cornered notch cut in the corner of the door or gate will accommodate the hinge casing 26 and afford a nice fit of the side of the casing 26 with the side of the notch. A tongue 28 projects laterally from the lower edge of the casing 26 and is provided with a number of apertures 29 to receive screws 30 for securing the hinge casing on to the door or gate.

While I have shown and described my invention in a preferred form, I am aware that various changes and modifications may be made without departing from the principles of my invention, the scope of which is to be determined by the appended claims.

I claim as my invention:

1. A double acting spring hinge comprising a bracket having spaced attaching plates 20 and an arm having an aperture with an annular seat around the aperture and a recess extending radially from the aperture between and communicating with the space formed between the side plates of the bracket, a bushing in the aperture having an annular flange rotatably engaged in the seat flush with the top of the arm and provided with a radially outwardly extending

arm disposed in the recess of the bracket, an adjusting member rotatably mounted in the side flanges of the bracket and extending across the recess, said adjusting member having threaded engagement with the radial arm and held against longitudinal movement to adjust the bushing, a spindle having a squared end fitting a socket in the bushing, and a hinge casing journaled on and oscillatable around the spindle.

2. A double acting spring hinge comprising a bracket having an arm with an aperture and a seat around the aperture, the bracket being open between its sides and communicating with the aperture and seat, a bushing rotatably mounted in the aperture and seat and provided with an arm disposed in the opening, a single adjusting member rotatably mounted in the sides of the bracket with its ends countersunk therein and having threaded engagement with the arm, said member being held from longitudinal movement to adjust the bushing rotatably, and a hinge casing adapted to be secured to a door and having a spindle connected to turn with the bushing.

WILLIAM J. KEENE.
